Primary Examiner — Barbara Fox*Assistant Examiner* — Chelsea Sealey(74) *Attorney, Agent, or Firm* — Studebaker & Brackett PC(57) **CLAIM**

The ornamental design for portable terminal, as shown and described.

DESCRIPTION

FIG. 1 is a front perspective view of a portable terminal showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof;

FIG. 9 is a rear view showing a state where a mounting member is attached to the portable terminal;

FIG. 10 is a right side view thereof;

FIG. 11 is a bottom view thereof;

FIG. 12 is a front perspective view showing a state where the mounting member is detached from the portable terminal; and,

FIG. 13 is a rear perspective view thereof.

The broken lines represent portions of the portable terminal that form no part of the claimed design.
